UNITED STATES PATENT OFFICE

93,090

DESIGN FOR A HAT RACK

Leon Cohen, Los Angeles, Calif.

Application May 31, 1934, Serial No. 51,973

Term of patent 14 years

To all whom it may concern:

Be it known that I, LEON COHEN, a citizen of the United States, residing at Los Angeles, in the county of Los Angeles and State of California, have invented a new, original, and ornamental Design for a Hat Rack, of which the following is a specification, reference being had to the accompanying drawing, forming part thereof.

Fig. 1 is a perspective view of the design.

Fig. 2 is a plan view of the design.

I claim:

The ornamental design for a hat rack as shown.

LEON COHEN.
